DEPOSITOR FOR CHOCOLATE
AND THE LIKEAllan Ashmead Tunley, Peterborough, England,
assignor to Baker Perkins Limited, Peterbor-
ough, EnglandApplication February 21, 1945, Serial No. 579,053
In Great Britain February 26, 1944

3 Claims. (Cl. 107—27)

1

This invention relates to machines for depositing chocolate, cream or other viscous liquid, in the mould trays of a continuously travelling conveyor, and is concerned with mechanism for oscillating the depositor to accord with the travel of the moulds during the depositing period to effect deposits either with no relative movement between the depositing nozzle and the mould cavities or to produce a predetermined relative movement to draw or spread the chocolate in the mould.

In known machines of the type to which the invention has reference, a fixed throw crank running at one revolution per deposit (or piston cycle) or (in a modification of the said type) a variable throw crank running at three revolutions per deposit, oscillates the depositor by means of a quadrant lever and adjustable link mechanism to draw or centre the deposits in the mould, under the control of a cam which varies the position of the quadrant fulcrum for purposes of skip (i. e. accommodating the interval between mould trays).

To deal with the different varieties of work, adjustments have to be made in the variable throw crank and quadrant link mechanism, and additional means including a cam and adjustable cam roller lever mounted on the depositor hopper are provided for modifying the oscillations produced in either the fixed throw or the variable throw crank species of machine.

The known mechanism is somewhat complicated and the operator has available a number of adjustments which are liable to lead to confusion; also certain of the devices are mounted on the depositor and partake of its oscillations, thus undesirably increasing the mass in motion. Moreover, the additional cam mechanism for modifying the oscillations involves a discontinuity of contact or lost motion between the modifying cam and its roller with the result that the operation may be abrupt or lacking in smoothness.

The aim of the present invention is to provide improvements which afford a simplification of the mechanism for oscillating or controlling the oscillations of a depositor of the kind in question, which not only reduces the cost of construction but offers more direct mechanical operation and provides an arrangement which does not add to the oscillating mass.

A further advantage achieved by the improvements lies in the fact that the number of adjustments required to attain any particular result is reduced and the work of the operator simplified and rendered less confusing.

2

The invention consists in providing alternatively selectable eccentric (or crank or cam) drives affording different timing or frequency of the quadrant lever oscillations and providing adjustment means for varying the quadrant link throw from maximum to a zero position coincident with the lever fulcrum, in order to afford oscillatory displacements either for any predetermined draw setting or for synchronizing the oscillatory displacement with and in the same sense as the mould travel, to make for example a series of deposits centred in a corresponding series of adjacent rows of small mould cavities.

The invention also consists in depositor oscillating mechanism comprising a quadrant lever having a skip controlled fulcrum with its axis intersected by the path of the axis of the quadrant link slider pivot, so that by adjustment the link stroke may be reduced to zero and a pair of eccentric (crank or cam) drives interchangeableably connectable to the quadrant lever.

A convenient mode, according to the invention, of effecting the interchangeable connection may be afforded by providing a detachable connecting rod adapted to be united to one or other of the eccentrics and to the quadrant lever, the preferred arrangement being that one eccentric is driven at the rate of three revolutions per deposit (or piston cycle) for draw motions while for synchronizing small deposits (such as above indicated) the other eccentric may be driven at one revolution per deposit (or piston cycle).

In the accompanying drawings:

Figure 1 is a side elevation of a depositor having oscillating mechanism according to the invention,

Figure 2 is an end view looking from the right in Figure 1, the hopper being removed, and

Figure 3 is a section on line 3—3 of Figure 1.

In carrying the invention into effect according to one mode as described by way of example, the depositor hopper 1 is pivotally mounted at 2 on a suitable frame 3 over the mould conveyor bed (not shown) so that it may be oscillated to and fro in the direction of the mould conveyor travel in known manner. Connected to the lower portion 4 of the hopper 1 is one end of a link 5 the other end of which is connected at 6 to one arm 7 of a bell-crank lever, the other arm 8 of which is connected at 9 to another link 10 (which may be referred to as the quadrant link) the outer end of which is pivotally mounted in a slider in a quadrant lever 11. The quadrant link 10 is provided with adjustment means 12 for adjusting its effective length

to vary the zone of operations of the deposit nozzle or outlet valve 13 longitudinally of the mould conveyor.

The quadrant lever 11 has an arcuate slot 14 in which the slider of the quadrant link 10 is displaceable by a screw adjustment device 15. The quadrant 11 carries a back plate 16 by which the quadrant is mounted on a fulcrum pivot pin 17 integral with the back plate the axis of pin 17 coinciding with the centre line of the quadrant arcuate slot 14 to enable the slider pivotal axis to be adjusted to coincide with the fulcrum axis when it is desired to reduce the motion communicated to the quadrant link 10 by the quadrant 11 to zero. The fulcrum pin 17 is pivotally connected to the end of arm 18 of a bell crank cam lever the other arm 19 of which cooperates with the skip cam 20.

The quadrant lever 11 has an operating arm 21 which is connectable to one or other of a pair of eccentrics to be described.

A constant speed drive shaft 22 is positioned in the depositor supporting frame 3 and carries a series of change-speed pinions 23 meshing with a corresponding series of pinions loosely mounted on a lay shaft 24 and selectively coupleable therewith through clutch means in known manner. By this arrangement the lay shaft 24 may be driven at any predetermined speed afforded by the appropriate selection of the change-speed pinions.

The drive shaft 22 also carries a gear 25 which meshes with a gear 26 for driving the skip cam 20.

Fixed conveniently on one end of the lay shaft 24 is an eccentric 27 (which may be hereinafter referred to as the short stroke eccentric) so that this eccentric makes one revolution per revolution of the lay shaft 24. Adjacent the short stroke eccentric 27 another eccentric 28 (which is called the long stroke eccentric) is mounted on a collar 29 loose on the lay shaft 24. The collar has a gear 30 which is driven through an appropriate train 31, 32 by a gear 33 fixed on the lay shaft, the train being devised so that for each revolution of the lay shaft 24 the long stroke eccentric makes three revolutions.

The long stroke eccentric 28 is intended for imparting to the depositor hopper 1 three oscillations per depositor piston cycle, the deposit or valve opening 13 being adjusted to take place towards the end of the forward oscillation and extending over the backward movement and part of the next forward oscillation, with a view to drawing the deposit out along the length of the mould and turning under or back the ends of the chocolate deposit.

The short stroke eccentric 27 is intended for oscillating the depositor 1 in such a manner that while the deposit is taking place substantially no relative movement exists between the mould travel and the depositing nozzle and may be used, for example, to make a deposit centrally in a series of rows of small mould cavities such as where there are four longitudinally disposed mould cavities per tray.

The strap of each eccentric 27, 28 is adapted to receive a plate 34 fixed to the end of an interchangeable connecting rod 35, the other end of which is detachably connectable to the drive receiving arm 21 of the quadrant lever 11. The plate 34 is adapted to be connected to one or other of the eccentric straps by set screws 36 having milled heads or by other suitable readily detachable means.

The quadrant end of the connecting rod 35 has a bush 37 through which a withdrawable pin 38 is adapted to be passed to engage with a pair of bored lugs or forked arm 21 of the quadrant.

5 The connecting rod 35 is united to the bush 37 towards one side of its central plane so that when the rod is detached from an eccentric strap and the quadrant bush pin 38 has been withdrawn, the rod 35 may be turned over to align with the 10 other eccentric. The connection of the rod 35 to the eccentric strap and with the quadrant is then established by manipulating the set screws 36 and reintroducing the withdrawable quadrant pin 38.

15 It will be understood that instead of eccentrics, cranks may be employed with a similar disconnectable rod or drive connection for the arm adapted for selective use, or that in place of either eccentric or cranks, appropriately shaped 20 cams may be used, in which case a common drive connection may be provided for the quadrant arm carrying a pair of levers having cam rollers arranged so that one or other may be engaged with the selector cam for the purpose of communicating the 1:1 or 3:1 drive to the quadrant.

25 It will also be appreciated that as the eccentric or like modifying drive for the quadrant is mounted in the framework, which carries the depositor hopper, and not upon the hopper itself, 30 the mass subject to oscillation is not increased by the weight of the modifying mechanism, which it will be understood should be kept as light as possible.

I claim:

35 1. In a machine for depositing chocolate and the like upon continuously travelling moulds, a hopper mounted for oscillation above the moulds and having a depositing nozzle, a pivotally mounted quadrant lever, linkage connecting the quadrant lever to the hopper, means for oscillating the lever and thereby the hopper comprising a drive shaft, a driven shaft, variable speed means connecting the shafts, a first drive means 40 directly driven by said driven shaft and rotating at the same speed as said driven shaft, a second drive means carried by said driven shaft, means driven by said driven shaft and operably connected with said second drive means to drive the same at a fixed speed different than the speed of said driven shaft and of said first drive means 45 and connecting means selectively connectible between said respective drive means and said quadrant lever to selectively couple the lever with the driven shaft at different ratios of oscillation for each revolution of said driven shaft.

50 2. In a machine for depositing chocolate and the like upon continuously travelling moulds, a hopper mounted for oscillation above the moulds and having a depositing nozzle, a pivotally mounted quadrant lever, linkage connecting the quadrant lever to the hopper including a driven shaft, a pair of eccentrics carried by said driven shaft, means for constantly driving one of 55 said eccentrics at a fixed speed different than the speed of the other eccentric and a connecting rod selectively directly connectible between said respective eccentrics and said quadrant lever to selectively couple the lever with the driven shaft 60 at different ratios of oscillation for each revolution of said driven shaft.

65 3. In a machine for depositing chocolate or the like upon continuously travelling moulds, a hopper mounted for oscillation above the moulds and having a depositing nozzle, a pivotally mounted 70

quadrant lever, adjustable linkage connecting the quadrant lever to the hopper, means for oscillating the lever including a drive shaft, a driven shaft, variable speed means coupling the shafts, a pair of eccentrics closely mounted on said driven shaft, means for driving the eccentrics at relatively different speeds, a pivot on said quadrant lever disposed parallel to the axes of the eccentrics on the driven shaft and at least coextensive in length with the axial extent of said eccentrics, and means comprising a connecting rod having at one end a bushing adapted to receive said pivot and the rod being offset towards one end from the transverse central plane of the bushing and the other end having means for selectively connecting the same to one of the eccentrics when the bushing is in one position on said pivot and to the other eccentric when the bushing is in a second position displaced axially 180 degrees from

the first position on said pivot, for selectively coupling the quadrant lever with the driven shaft at different ratios of oscillation for each revolution of said driven shaft.

ALLAN ASHMEAD TUNLEY.
